UNITED STATES PATENT OFFICE

JESSIE H. McCREARY, OF ANDERSON, INDIANA

DESIGN FOR A HOLDER FOR A THERMOMETER OR THE LIKE

Application filed February 23, 1933. Serial No. 47,302. Term of patent 7 years.

To all whom it may concern:

Be it known that I, JESSIE H. McCREARY, a citizen of the United States residing in the city of Anderson, county of Madison, Indiana, have invented a new, original, and ornamental Design for a Holder for a Thermometer, or the like, of which the following is a specification, reference being had to the accompanying drawing, forming a part thereof, and wherein the figure is a front elevational view of the holder for a thermometer, or the like, showing my new design.

The holder has no material thickness.

I claim:

The ornamental design for a holder for a thermometer, or the like, as shown and described.

JESSIE H. McCREARY.
